FISHTAIL PROPELLER

Leon J. Weatherwax, Toledo, Wash., assignor of
one-half to Robert B. Menehee, Toledo, Wash.

Application August 25, 1938, Serial No. 226,788

1 Claim. (Cl. 170—165)

The invention relates to a fishtail propeller and more especially to a twin or duplex oscillatory blade propeller.

The primary object of the invention is the provision of a propeller of this character, wherein several blades oscillate relative to each other with respect to an axis common thereto and in the operation will move back and forth in air or water giving greater driving force and minimizing slip, the propeller being of novel construction.

Another object of the invention is the provision of a propeller of this character, wherein the fins or blades are of semi-flexing quality to assure perfect working thereof with resultant maximum driving power and eliminating damage when meeting an obstruction.

A further object of the invention is the provision of a propeller of this character, which is simple in its construction, thoroughly reliable and efficient in operation, being possessed of few parts resulting in strength and durability, and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is a plan view partly in section of the propeller constructed in accordance with the invention.

Figure 2 is a vertical longitudinal sectional view partly in elevation.

Figure 3 is a sectional view taken on the line 3—3 of Figure 1 looking in the direction of the arrows.

Figure 4 is a sectional view taken on the line 4—4 of Figure 2.

Similar reference characters indicate corresponding parts throughout the several views in the drawings.

Referring to the drawings in detail, A designates generally a housing of substantially elliptical contour and effecting an enclosure for a driven rotary element 10, being made fast to a driving arbor or shaft 11, which is centrally located in said element and is perpendicularly disposed within the housing, being journaled at its lower reduced end 12 in said housing and also in a shaft casing, a portion thereof being indicated at 13. The shaft casing 13 is fixed in a collar extension 14 formed integral with the housing A

and such shaft is operated from any suitable source of power.

The element 10 has formed at opposite sides thereof reversely disposed eccentrics or cams 15 and 16, respectively, about which are eccentric straps 17, these having rod-like arms 18. The arms 18 are telescoped within hollow tube formations 19 provided with turning hubs 20, these swinging on a vertical axis in a common perpendicular direction with respect to said tubular extensions 19. The extensions 19 protrude through a clearance 21 provided therefor in the housing A.

The tubular extensions 19 carry semi-flexible blades 22, preferably made from flexible steel of the marginal contour as shown in Figure 2 of the drawings. Opposite faces of these blades are provided with main and branch ribs 23 and 24, respectively, the latter being angled to the horizontal while the rib 23 is longitudinally directed to the said blades. The turning arbors or axles 20 for the tubular extensions 19 are indicated at 25, having suitable bearings in the housing and one within the other of the hub portions 20.

The blades 22 are oscillated in reverse directions to each other and rotate through a portion 25 of the arc of a circle in parallel planes one above the other on rotation of the cams or eccentrics 16 and the paths or wakes of both blades being sinuous when the device is moving. The twin relationship or duplexity of the propeller blades assures maximum driving force and less slip in the operation of the propeller.

The blades 22 effect an oscillatory twin fishtail propeller.

The arms 18 slidably fit within the tubular extensions 19 moving inwardly and outwardly with respect thereto on oscillation activity of each blade.

The housing at its lowermost portion has a rudder formation 26.

The operation of the propeller should be clearly understood from the foregoing taken in connection with the drawings and therefore an extended explanation has been omitted.

What is claimed is:

A propeller of the character described comprising a housing, tubular extensions projected from said housing, rotatable through a portion of the arc of a circle in parallel planes one above the other and having hubs swingable on an axis common to said tubular extensions, and blades carried by said extensions.
